UNITED STATES PATENT OFFICE.

LOUIS M. ROSENBERG, OF NEW YORK, N. Y.

DESIGN FOR A BELT-BUCKLE.

No. 40,208.

Specification for Design.

Patented Aug. 10, 1909.

Application filed May 14, 1909. Serial No. 496,081. Term of patent 14 years.

To all whom it may concern:

Be it known that I, LOUIS M. ROSENBERG, a citizen of the United States, residing in the city of New York, borough of Brooklyn, county of Kings, and State of New York, have invented a new, original, and ornamental Design for Belt-Buckles, of which the following is a specification, reference being had to the accompanying drawing, forming part hereof, wherein—

Figure 1 is a perspective view of the buckle showing my new design; and Fig. 2 is a front view of the face thereof.

I claim—

The ornamental design for a belt buckle as shown.

LOUIS M. ROSENBERG.
